UNITED STATES PATENT OFFICE.

HOOD PITTS, OF AUSTIN, TEXAS, ASSIGNOR OF ONE-HALF TO FRANK M. COVERT, OF AUSTIN, TEXAS.

SWITCH.

1,139,903.

Specification of Letters Patent.

Patented May 18, 1915.

Application filed December 24, 1912, Serial No. 738,495. Renewed December 10, 1914. Serial No. 876,471.

To all whom it may concern:

Be it known that I, Hood Pitts, a citizen of the United States, residing at Austin, in the county of Travis and State of Texas, have invented certain new and useful Improvements in Switches, of which the following is a specification, reference being had to the accompanying drawings.

This invention relates to an improved switch and more particularly to an operator's switch for electrically controlled elevator door or gate operating mechanism of that character shown and described in my application for patent filed Jan. 11, 1913, Serial No. 741,604, the invention having for its primary object to provide a simple, efficient and easily operated switch for this purpose, the movable element of which is mounted upon the lever of the car controller, thereby insuring the proper closing of the door or gate before the car leaves the floor landing.

Another object of the invention resides in the provision of a handle for the control lever and a spring actuated pin mounted therein to close the electric circuit when the lever is in its normal position, and means coacting with said pin to hold the same and lock the lever when the switch is closed.

A still further object of the invention is to provide an operator's switch for the above purpose which comprises but few elements of simple form, and is not therefore liable to get out of order and which may be manufactured and installed at comparatively small cost.

With the above and other objects in view, as will become apparent as the description proceeds, the invention consists in certain constructions, combinations and arrangements of the parts that I shall hereinafter fully describe and claim.

For a full understanding of the invention, reference is to be had to the following description and accompanying drawings, in which—

Figure 1 is a side elevation illustrating my improved operator's switch arranged in the elevator car and showing the door or gate operating mechanism and circuit therefor; Fig. 2 is an enlarged vertical section through the switch; Fig. 3 is a section taken on the line 3—3 of Fig. 2; Fig. 4 is a section taken on the line 4—4 of Fig. 2; Fig. 5

is a detail perspective view of the movable circuit closing element or pin; and Fig. 6 is a detail sectional view of the floor selector switch.

Referring in detail to the drawings, 5 designates an elevator car of any approved 60 form or construction, said car being provided with the usual controller 6.

7 indicates generally the elevator door or gate operating mechanism which is actuated from the shaft of an electric motor 8. This 65 motor obtains its supply of current from the generator 9 and in the motor circuit, a floor selector switch 10 is arranged.

As the specific construction of this switch is fully shown and described in my co-pending application for patent, filed coincident herewith, Ser. No. 738,494, the same will not be set forth in detail in the present specification. It will suffice to state that the switch 10 includes an armature plate 11 75 which is mounted for movement toward and from an electromagnet 12 mounted upon the elevator car 5. The switch is so arranged that when the car is brought to a stop with the magnet 12 in proper relation 80 to the switch, the magnet will be energized and the armature attracted so as to move its arm to make the proper contacts to throw into circuit the mechanism for opening the door. When the controller handle is moved 85 to start the car, its first movement will be to break the circuit to the magnet thereby releasing the armature. The armature arm will now be moved away from the door opening contacts and into contact with 90 others and complete the circuits to move the door to its closed position. Should the car be started without breaking the magnet circuit at the contact 14, the magnet will be moved from contact with the armature and 95 the door will be closed in the same manner as if the circuit be broken at the contact 14.

The electromagnet 12 is fed from the light circuit of the car or other source of electric current supply indicated at 13, and the terminals of the magnet are connected to a stationary contact 14 mounted in a casting 15 arranged in any suitable manner upon one of the car walls and to the source of current supply, respectively. In the casting 15, a movable contact member 16 is arranged which is mounted upon the end of a spring blade 17. This movable spring blade

is connected by means of a wire 18 to the current supply source 13.

19 indicates the lever of the controller 6. This lever is provided with a tubular or hollow handle 20, one end of which is yieldingly held within an annular recess or seat 21 provided in the outer end of the lever 19. This annular recess 21 is concentrically related to a threaded opening 22 provided in the end of the lever in which one end of a tube 23 is threaded. A portion of the bore of the hollow handle 20 is contracted or reduced in diameter as indicated at 24 to closely surround the tube 23 which projects into the larger portion of the handle bore. This tube upon its outer end is provided with an integral head or nut 25 against which one end of a coil spring 26 bears. The other end of this spring is suitably secured to the movable lever handle 20. A rod or pin 27 is loosely disposed through the tube or sleeve 23 and is provided upon its outer end with an exteriorly threaded head 28 for engagement with interior threads of the handle bore. A coil spring 29 is arranged within the outer end of the handle 20 upon the pin 27. One end of this spring is fixed to the head 28 and the other end thereof bears against the end of the tube 23, said spring acting to normally force the handle 20 and the pin 27 carried thereby outwardly. The inner end of this pin is adapted to be received through an opening 30 in the front wall of the casing 15, and said pin is provided with an annular reduced portion forming a groove 31. The extremity of the pin is rounded or convex as shown and is adapted to engage the opposed rollers 32 mounted upon the angular arms or levers 33 fulcrumed as at 34 upon the front wall of the casing 15. These rollers are forced or spread apart by the pin 27 against the action of the coil springs 35 which are connected to the levers 33 and to bracket arms 36 secured to the casing wall. The end of the pin 27 engages the spring blade 17 and forces the contact member 16 mounted upon said blade into engagement with the relatively stationary contact member 14, said pin being held against reverse movement by means of the rollers 32, the spring 35 being sufficiently strong to overcome the tendency of the spring 29 to force the handle and pin outwardly to their normal positions. The contact member 14 is preferably held yieldingly in opposed relation to the movable contact 16 by means of a spring 37 so as to compensate for wear of the contacts and insure the proper closing of the circuit.

From the foregoing it will be seen that when the control lever is brought to its normal position to stop the car at the floor landing, the switch pin 27 is directly opposite the opening 30 in the wall of the casing 15 or housing 15. In the movement of the

lever, the operator pulls outwardly upon the handle 20, so that the movement of the pin 27 will not be obstructed. Upon release of the handle the springs 26 and 29 move the handle 20 to its normal position and seat 70 the same in the annular groove 21 in the end of the control lever, the end of the pin 27 moving through the opening 30 and into engagement with the rollers 32 and the movable blade 17. The rollers 32 engage in the 75 annular groove 31 in the end of the pin as above explained, overcoming the reverse action of the spring 29 and holding the contact 16 in engagement with the contact 14, thereby closing the circuit through the electromagnet 12 and energizing the same to attract the armature plate 11 and thus actuate the floor selector switch to close the circuit for the door operating mechanism 7 and move the elevator door or gate to its 80 open position. As the pin 27 must first be retracted from the casing 15, thereby breaking the circuit of the magnet 12, before the control lever can be moved to start the car, it will be obvious that the position of the 85 movable element of the floor selector switch 10 is reversed to reverse the operation of the motor and close the elevator door or gate before the car leaves the floor landing. Liability of accident and serious injury 90 caused by persons falling down the elevator shaft when the door or gate is left open through inadvertence or negligence on the part of the operator, will thus be obviated.

From the foregoing, it is thought that the 100 construction and manner of operation of my improved switch will be clearly understood.

As the device comprises but few elements in its construction, it will be obvious that the same is highly efficient and strong and durable in practical use. By mounting the movable element of the switch directly upon the handle of the operator's control lever, it will be apparent that the switch may be manipulated with ease and quickness and the necessity of the car operator leaving his station is thus avoided.

While I have illustrated and described what at the present time is deemed to be the preferable embodiment of the invention, it 115 is obvious that the device is susceptible of various modifications in the form, proportions and minor details of construction such as may be necessitated in order to adapt the invention to peculiar existing conditions, 120 without departing from the principle involved or sacrificing any of the essential features thereof.

The specific form of door operating mechanism shown is not claimed in this application but is made the subject matter of my co-pending application for patent for elevator door operating and locking devices filed January 11, 1913 and numbered serially 741,604. The particular form of floor se- 130

lector switch shown herein is not claimed in this application but is made the subject of my co-pending application entitled Floor selector switch, filed December 24, 1912 and numbered serially 738,496.

Having thus described the invention, what is claimed is:

1. The combination with a moving element, a device for controlling the movements of the element, of an electric circuit carried by the element, a magnet in the circuit, a switch in the circuit, means carried by the movable element of the device for engaging the contacts of said switch, and an armature coöperating with said magnet, the armature being stationary relatively to the movement of the element.

2. The combination with a moving element, a device for controlling the movements of the same, and a lever for operating the device, of an electro-magnet carried by the element, a circuit for the magnet, an operator's switch including stationary and movable contacts arranged in the circuit, and means mounted on the lever and movable in relation thereto to engage the contacts and close the magnet circuit, and an armature coöperating with the magnet, said armature being stationary relatively to the movement of the element.

3. The combination with a moving element, a device for controlling the movements of the same and a lever for operating the device, of an electro-magnet carried by the element, a circuit for the magnet, a switch including stationary and movable contacts arranged in the magnet circuit, and means mounted upon the end of the lever and movable with relation thereto to engage the movable contact with the stationary contact and close the magnet circuit and an armature coöperating with the magnet, said armature being stationary relatively to the movement of the element.

4. The combination with a moving element, a device for controlling the movements of the same and a lever for operating the device, of an electro-magnet carried by the element, a circuit for the magnet, a switch including stationary and movable contacts arranged in the circuit, means carried by and movable relatively with the lever and operating to engage the movable contact with the stationary contact and close the circuit, means for permitting such engagement only when said lever is in position to stop the moving element, a handle on the lever, said handle carrying the contact operating means and an armature coöperating with the magnet.

5. The combination with a moving element, a device for controlling the movements of the same and a lever for operating the device, of an electro-magnet carried by the element, a circuit for the magnet, a

switch including stationary and movable contacts arranged in the circuit, means carried by and movable relatively with the lever and operating to engage the movable contact with the stationary contact and close the circuit, means for permitting such engagement only when said lever is in position to stop the moving element, a relatively movable handle on the lever, said handle carrying the contact operating means and an armature coöperating with the magnet.

6. The combination with a moving element, a device for controlling the movements of the same and a lever for operating the device, of an electro-magnet carried by the element, a circuit for the magnet, a switch including stationary and movable contacts arranged in the circuit, means carried by and movable relatively with the lever and operating to engage the movable contact with the stationary contact and close the circuit when said lever is in position to stop the moving element, said means operating to prevent movement of the controller lever to start the moving element without first breaking the circuit, and an armature coöperating with the magnet.

7. The combination with a moving element, a device for controlling the movements of the same and a lever for operating the device, of an electro-magnet carried by the element, a circuit for the magnet, a switch including stationary and movable contacts arranged in the circuit, means carried by and movable relatively with the lever and operating to engage the movable contact with the stationary contact and close the circuit when said lever is in position to stop the moving element, said means acting to prevent movement of the controller lever to start the moving element while the magnet circuit is closed, and an armature coöperating with the magnet.

8. The combination with a moving element, a device for controlling the movements of the same and a lever for operating the device, of an electro-magnet carried by the element, a circuit for the magnet, a switch including stationary and movable contacts arranged in the circuit, spring pressed means carried by and movable relatively with the lever and operating to engage the movable contact with the stationary contact and close the circuit when said lever is in position to stop the moving element, a handle on the lever, said handle being connected to the contact operating means and an armature coöperating with the magnet.

9. The combination with a moving element, a device for controlling the movements of the same and a lever for operating the device, of an electro-magnet carried by the element, a circuit for the magnet, a switch including stationary and movable

- contacts arranged in the circuit, means carried by and movable relatively with the lever and operating to engage the movable contact with the stationary contact and close the circuit when said lever is in position to stop the moving element, said means acting to lock the controller lever in such position, and an armature coöperating with the magnet.
10. The combination with a moving element, a device for controlling the movements of the same and a lever for operating the device, of an electro-magnet carried by the element, a circuit for the magnet, a switch including stationary and movable contacts arranged in the circuit, spring pressed means carried by and movable relatively with the lever and operating to engage the movable contact with the stationary contact and close the circuit when said lever is in position to stop the moving element, said means acting to lock the controller lever against movement while the circuit is closed, and an armature coöperating with the magnet.
11. The combination with a moving element, a device for controlling the movements of the same and a lever for operating the device, of an electro-magnet carried by the element, a circuit for the magnet, a switch including stationary and movable contacts arranged in the circuit, means carried by and movable relatively with the lever and operating to engage the movable contact with the stationary contact and close the circuit when said lever is in position to stop the moving element, means coöperating with the circuit closing means to yieldingly hold the same against retraction, and an armature coöperating with the magnet.
12. The combination with a moving element, a device for controlling the movements of the same and a lever for operating the device, of an electro-magnet carried by the element, a circuit for the magnet, a switch including stationary and movable contacts arranged in the circuit, spring pressed means carried by and movable relatively with the lever and operating to engage the movable contact with the stationary contact and close the circuit when said lever is in position to stop the moving element, means coöperating with the circuit closing means to hold the same against retraction and lock the lever in position, and an armature coöperating with the magnet.
13. The combination with a moving element, a device for controlling the movements of the same and a lever for operating the device, of an electro-magnet carried by the element, a circuit for the magnet, a switch including stationary and movable contacts arranged in the circuit, spring pressed means carried by and movable relatively with the lever and operating to engage the movable contact with the stationary contact and close the circuit when said lever is in position to stop the moving element, means coöperating with the circuit closing means to yieldingly hold the same against retraction and lock the lever in position, and an armature coöperating with the magnet.
14. The combination with a moving element, a device for controlling the movements of the same and a lever for operating the device, of an electro-magnet carried by the element, a circuit for the magnet, a switch including stationary and movable contacts arranged in the circuit, spring pressed means carried by and movable relatively with the lever and operating to engage the movable contact with the stationary contact and close the circuit when said lever is in position to stop the moving element, means coöperating with the circuit closing means to yieldingly hold the same against retraction and lock the lever in position, and an armature coöperating with the magnet.
15. The combination with a moving element, a device for controlling the movements of the same and a lever for operating the device, of an electro-magnet carried by the element, a circuit for the magnet, a switch including stationary and movable contacts arranged in the circuit, a handle movably mounted on the lever, a circuit closing device carried by said handle, means for holding the handle against movement and acting to engage said device with the movable contact carrying member to close the circuit when the lever is in position to stop the moving element, and additional means co-acting with said device to hold the same against retraction and lock the lever while the circuit is closed, and an armature coöperating with the magnet.
16. The combination with a moving element, a device for controlling the movements of the same and a lever for operating the device, of an electro-magnet carried by the element, a circuit for the magnet, a switch including stationary and movable contacts arranged in the circuit, a handle movably mounted on the lever, a circuit closing device carried by said handle, means for yieldingly holding the handle against movement and acting to engage said device with the movable contact carrying member to close the circuit when the lever is in position to stop the moving element, and additional means co-acting with said device to hold the same against retraction and lock the lever while the circuit is closed, and an armature coöperating with the magnet.
17. The combination with a moving element, a device for controlling the movements of the same and a lever for operating the device, of an electro-magnet carried by the

element, a circuit for the magnet, a switch including stationary and movable contacts arranged in the circuit, a hollow handle mounted upon the end of the lever, a circuit closing device extending through said handle and connected thereto, springs arranged within said handle and normally holding the same against movement, said handle being movable, when the lever is in position to stop the moving element, to engage the circuit closing device with the movable contact carrying member and close the circuit, opposed yieldingly held members to co-act with the circuit closing device and hold the same against retraction, and an armature coöperating with the magnet.

18. The combination with a moving element, a device for controlling the movements of the same and a lever for operating the device, of an electro-magnet carried by the element, a circuit for the magnet, a switch including stationary and movable contacts arranged in the circuit, a handle carried by the lever, a movable, yieldingly held device mounted in the handle and adapted to engage the movable with the stationary contact and close the magnet circuit when the lever is in position to stop the moving element, means co-acting with the circuit closing device to hold the same against retraction and lock the controller lever in position, and an armature coöperating with the magnet.

19. The combination with a moving element, a device for controlling the movements of the same and a lever for operating the device, of an electro-magnet carried by the element, a circuit for the magnet, a switch including stationary and movable contacts arranged in the circuit, a movable spring held handle mounted upon the lever, a circuit closing pin carried by the handle to engage the movable contact with the stationary contact and close the circuit when the moving element is at rest, opposed movable members co-acting with the pin to hold it against retraction and an armature coöperating with the magnet.

20. The combination with a moving element, a device for controlling the movements of the same and a lever for operating the device, of an electro-magnet carried by the element, a circuit for the magnet, a switch including stationary and movable contacts arranged in the circuit, a movable spring held handle mounted upon the lever, a circuit closing pin carried by the handle to engage the movable contact with the stationary contact and close the circuit when the moving element is at rest, opposed spring pressed rollers co-acting with the pin to hold it against retraction and an armature coöperating with the magnet.

21. The combination with a moving element, a device for controlling the move-

ments of the same and a lever for operating the device, of an electro-magnet carried by the element, a circuit for the magnet, a switch including stationary and movable contacts arranged in the circuit, a spring held movable handle on the lever, a pin carried by the handle and movable therewith to engage the movable contact with the stationary contact and make the circuit, a plurality of yieldingly mounted elements co-acting with the pin to hold the same against retraction and lock the lever while the circuit is closed, and an armature coöperating with the magnet.

22. The combination with a moving element, a device for controlling the movements of the same and a lever for operating the device, of an electro-magnet carried by the element, a circuit for the magnet, a switch including stationary and movable contacts arranged in the circuit, a spring held movable handle on the lever, a pin carried by the handle and movable therewith to engage the movable contact with the stationary contact and make the circuit, said pin being provided at one end with an annular groove, a plurality of yieldingly mounted elements co-acting with the groove to hold the same against retraction and lock the lever while the circuit is closed, and an armature coöperating with the magnet.

23. The combination with a moving element, a device for controlling the movements of the same and a lever for operating the device, of an electro-magnet carried by the element, a circuit for the magnet, a switch including stationary and movable contacts arranged in the circuit, a casing for the switch, an opening in the casing, a spring held movable pin carried in the control lever and movable through the opening to close the circuit when the lever is in position to bring the car to rest, an annular groove in the pin, levers mounted in the casing, rollers carried by the levers to engage the groove, springs acting on the levers to hold the rollers in the groove to prevent retraction of the pin and to lock the control lever in position when the circuit is closed and an armature coöperating with the magnet.

24. The combination with a moving element, a device for controlling the movements of the same, and a lever for operating the device, a sleeve carried by the lever, of an electromagnet carried by the element, a circuit for the magnet, a switch including movable and stationary contacts arranged in the circuit, a handle slidably mounted on the sleeve, a pin carried by the handle and adapted to engage the movable contact with the stationary contact and close the magnet circuit when the lever is in position to stop the movement of the element, means co-act-

ing with the pin to hold the same against retraction and to lock the lever in position; a spring between the sleeve and the pin to normally hold the latter away from the 5 movable contact, and an armature coöperating with the magnet.

In testimony whereof I hereunto affix my signature in the presence of two witnesses.

HOOD PITTS.
